VARIABLE CONDENSER

Samuel Cohen, Brooklyn, N. Y., assignor to General Instrument Corporation, New York, N. Y., a corporation of New York

Application February 2, 1932, Serial No. 590,488

4 Claims. (Cl. 175—41.5)

My invention relates broadly to variable electrical condensers and more particularly to an improved construction of a multiple variable condenser.

5 One of the objects of my invention is to provide a simplified construction of multiple unit variable condenser which is capable of quantity production at low cost and adapted for simplified assembly processes.

10 Another object of my invention is to provide a simplified construction of multiple unit variable condenser wherein sets of stator plates may be mounted within a condenser frame by supporting the stator plates on downwardly depending insulated members suspended from strip members supported by the condenser frame.

15 Still another object of my invention is to provide a simplified method of assembly for the stator plates of a multiple unit variable condenser wherein the sets of stator plates may be insulatingly mounted in predetermined spaced relation as independent units from longitudinally extending strip members supported by the condenser frame.

20 A still further object of my invention is to provide a construction of multiple variable condenser in which the stator units are suspended laterally of a condenser chassis between two longitudinally extending strip members supported by the end plates and laterally extending intermediate shield plates of the multiple variable condenser chassis.

25 Other and further objects of my invention reside in the method of assembly and construction of multiple variable condensers as set forth more fully in the specification hereinafter following by reference to the accompanying drawings, in which:

30 Figure 1 is a top plan view of a condenser constructed in accordance with my invention; Fig. 2 is a front elevation thereof; Fig. 3 is a similar view of the opposite side; Figs. 4, 5 and 6 are transverse, vertical, sectional views respectively taken on correspondingly numbered lines of Fig. 1; Figs. 7 and 8 are fragmentary horizontal sectional views taken on correspondingly numbered lines of Fig. 2; Fig. 9 is a horizontal sectional view taken on line 9—9 of Fig. 6; Fig. 10 is a detailed transverse vertical sectional view on line 10—10 of Fig. 6 showing the insulated stop between the rotor and stator plates; Fig. 11 is a fragmentary perspective view of the upper edge portions of the rotor plates of the condenser; Fig. 12 is a detailed perspective view of the insulation stop;

Fig. 13 is a perspective view of the series of transversely extending plates constituting part of my improved condenser; Fig. 14 is a perspective view of the base plate; and Fig. 15 is a perspective view of the pair of longitudinally extending strips forming part of my improved condenser.

35 Referring to the drawings in detail, reference character 1 designates the lower portion of the pressed metal frame of the multiple variable condenser having upstanding side walls 2. The upstanding side walls 2 each have lugs 2a on opposite ends thereof. The lower portion of the frame 1 has horizontally projecting lugs 2b formed thereon. End plates 3 are secured to the ends of the lower portion of the frame 1, apertures 3a and 3b being formed in the end plates 3 to permit the passage of the lugs 2a and 2b, respectively. The lugs 2a and 2b when passed through the apertures 3a and 3b in the end plates 3 are swaged over for rigidly securing the end plates in erect position with respect to the lower portion of the condenser frame at 1. The lower portion of the condenser frame 1 is provided with stamped cutouts 1c and bosses 1d. Suitable securing means may extend through the bosses 1d for anchoring the condenser chassis in position with respect to the frame of a broadcast radio receiver with which the condenser is adapted to be associated. The condenser units extend laterally of the condenser frame and comprise sets of stator plates 10 and cooperating rotor plates 14. When assembled the sets of stator and rotor plates are electrostatically shielded from each other by means of intermediate plates 4. Intermediate plates 4 are provided with side cut out portions 4c with tongues or lugs 4d projecting thereon. The lower portion of the shield plates 4 is provided with projecting tongues or lugs 4b. The shield plate 4 is also provided with vertically extending slots 4a positioned as shown. Apertures 12b are formed in the shield plates 4 and adapted to be aligned with the apertures 12a in the end plates 3 through which the rotatable

40 shaft 12 is arranged to pass. A pair of longitudinally extending strip members 5 are secured to the shield plates 4 by means of the tongues 4d on the shield plates 4, which tongues extend through apertures 5d in strips 5 and are swaged over for establishing a rigid mechanical connection between the longitudinally extending strips 5 and the frame of the condenser. The longitudinally extending strips 5 are provided with countersunk apertures 5e

therein through which rivet members 7, connected with depending insulated members 6, are secured. The insulated depending members 6 are suspended from the longitudinally extending strips 5 and provide mounting means for the stator plate units. Each of the stator plate units consists of a plurality of plates 10 having lugs 10a and 10b formed thereon and engaged by the members 8 which provide rigid supports for the stator plates 10. The members 8 have channelways extending therethrough normal to the planes of the stator plates 10 and through these channelways there extends tie bars 11 which are screw threaded to receive screws 9 which extend through apertures 9a in insulated members 6, through the sheet metal of member 8, and into the screw threads in tie bars 11. In order to clearly illustrate the invention I have in Figs. 1, 7 and 8 shown the stator units with one end plate removed thereby showing the arrangement of the apertures 8a and 8b in members 8 through which the lugs 10a and 10b of the stator plates are arranged to pass. After the stator units are assembled in predetermined spaced relation depending from the longitudinally extending strips 5 and supported by the intermediate shield plates 4 with the lugs or tongues 4d swaged over, the condenser frame is prepared to receive the end plates 3. The end plates 3 are then moved toward each end of the condenser chassis so that the tongues 2a and 2b on the lower portion 1 of the condenser frame and the lugs 5c on the longitudinally extending strips 5 are aligned with and passed through the apertures 3a, 3b and 3c in the end plates 3. Thereafter, the lugs 2a, 2b and 5c are swaged over for establishing a rigid connection between the longitudinally extending strips 5, the end plates 3 and the lower portion of the condenser frame 1.

It will be observed that in the assembly process the insulated members 6 are first riveted by means of rivets 7 to one of the longitudinally extending strips 5, the strip 5 being secured to the edges of intermediate shield plates 4 by means of lugs 4d passing through apertures 5d in the aforementioned strip 5. The opposite strip 5 may then be applied to the insulated members 6 on the other sides of the stator units and connected to the opposite edges of the intermediate shield plates 4 by tongues 4d projecting through apertures 5d in the opposite strip 5. The stator units including the intermediate shield plates 4 may now be assembled into the condenser frame by lowering the shield plates 4 into position where slots 4a embrace the upstanding side walls 2 of the lower portion of the condenser frame 1, the tongues 4b projecting through the apertures 2c in frame 1 and being swaged over to rigidly connect the parts of the condenser frame. The end plates 3 are now secured in position by moving the plates and the apertures 3a, 3b and 3c into registry with tongues 2a, 2b and 5c and swaging the tongues for securing the frame in rigid position. The rotary shaft 12 is passed longitudinally through the apertures 12a and 12b in the end plates and the intermediate shield plates 4, respectively. Journals 12a in the end plates 3 house ball bearing races in which the rotary shaft 12 revolves. Plate member 12c closes the ball race formed in the end plate 3 shown at the left in Fig. 1 and permits rotation of shaft 12 while maintaining the rotor plates in proper position. Shaft 12 carries sleeve members 15 which are grooved to support the rotor plates 14 in spaced relation and adapted to be interleaved

with the sets of stator plates 10. The rotor plates 14 are keyed at one edge thereof by means of a key strip 16 which fits into grooves formed in the edges of the rotor plates 14.

Figure 11 shows a fragmentary view of the rotor plates provided with aligned grooves 17 offset at 17a to receive the double T-shaped insulation member 18. The double T-shaped insulation member 18 has the upper portion 18a thereof fitted within groove 17a immediately behind key strip 16. The depending parts 18b of the double T-shaped strip extend between adjacent rotor plates 14 and provide a projecting strip engageable with the offset edges 10c of the stator plates 10 when the condenser is moved to maximum capacity position, for preventing any short-circuit between the rotor and stator plates. The rotor plates are fixed on shaft 12 by means of set screws 19 which extend through the sleeves 15 and serve to anchor the rotor plates on the shaft 12. A sufficient degree of friction is introduced at each of the condenser stages to permit precision adjustment of the variable condenser to any selected position. For this purpose I employ spring members 20 engageable with the end plate 3 or intermediate shield plate 4 and bearing against the end of sleeve 15.

At one side of the condenser I provide trimmer condenser units supported by the insulated members 6. The trimmer condenser units are constituted by resilient plate members 21 having a connecting lug 22 and being secured by means of screw members 9. Each plate member 21 has a resilient offset portion 24 to allow lateral adjustment of the plate 21 with respect to the strip 5 under control of set screw 25. Set screw 25 is insulated from movable plate 21 by means of washer member 26 and by reason of the enlarged aperture in plate 21 through which screw 25 passes. A sheet of mica or other insulated material 27 provides means for insulating adjustable plate 21 from strip member 5. Inasmuch as strip member 5 is grounded to the frame of the condenser and to the rotatable shaft 12 and rotor plates 14 carried thereby, and in view of the fact that stator plates 10 are connected through member 8 and screws 9 with trimmer condenser plate 21, each trimmer condenser is thereby placed in shunt with the coordinated sets of stator and rotor plates so that an adjustment of maximum to minimum capacity ratio may be effected for each condenser stage. Each set of rotor plates is provided with an an end plate which is formed with radially extending slots which I have shown at 28 in Fig. 4. These slots extend less than one-half the radius of the rotor plate and serve to divide the rotor plate into a plurality of segments which may be bent toward or away from the stator plates for changing the effective capacity of each condenser stage and correspondingly permitting a balance of the amplifier circuits, with which the tuning condenser is connected, to be obtained. Individual selective adjustment of each of the trimmer condensers and separate adjustment of each of the slotted rotor plates is permitted for adjusting the condenser for precision operation.

I have found that the method of mounting the stator plates through the depending insulating members independent of the lower portion of the condenser frame, greatly facilitates and simplifies the manufacture of condensers. While I have described my invention in certain preferred embodiments I desire that it be understood that modifications may be made and that no limita-

tions upon my invention are intended other than are imposed by the scope of the appended claims.

What I claim as new and desire to secure by Letters Patent of the United States is as follows:

5 1. A multiple variable condenser comprising a channel shaped chassis, an end plate secured at each end of said chassis, a pair of flat metallic strips extending between said end plates longitudinally of said chassis on opposite sides thereof
10 and above the edge extremities of the walls of said channel shaped chassis, insulated plate members secured at their upper ends to said strips, shield plates extending transversely of said chassis and having oppositely disposed recesses
15 therein receiving said strips, tongues in said recesses engaged through said strips between the insulated plate members, stator units extending transversely of said chassis between the shield plates and end plates and consisting of spaced plates secured at their ends to the insulated plate members and spaced from said chassis, a shaft journaled through said end plates, and rotor units carried by said shaft in position whereby plates of the rotor units may interleave with plates of
20 companion stator units.

2. A multiple variable condenser comprising a supporting plate formed of sheet metal and having side portions bent to form upstanding flanges, said supporting plate having slots formed transversely therein adjacent said flanges and tongues provided at ends of the flanges and at ends of the plate adjacent the flanges, end plates, and intermediate plates, the end plates having slots to receive said tongues and firmly secure the end plates to the supporting plate and flanges thereof, and the intermediate plates having slots leading from their lower edges to receive said flanges, tongues extending from lower edges of the intermediate plates and engaged through the slots of
30 the supporting plate to secure the intermediate plates thereto, independent metal strips extending from one end plate to the other above the edges of said flanges and in planes parallel thereto and having tongues at their ends engaged
35 through other slots formed in the end plates, said strips being seated in recesses formed in ends of the intermediate plates and formed with slots receiving tongues carried by the intermediate plates to secure the intermediate plates to the strips, insulating plates fixed to said strips and depending therefrom between the end plates and intermediate plates, sets of stator plates extending between the intermediate plates and end plates and having end brackets secured to the
40 insulating plates to mount the stator plates in

spacial relation to said supporting plate and its flanges, a rotatable shaft journaled in said end plates and extending through aligned openings formed in the intermediate plates, and sets of rotor plates carried by said shaft to turn with the shaft and adapted to be interleaved with the plates of companion sets of stator plates.

5 3. A multiple variable condenser comprising a supporting plate formed of sheet metal and having side portions bent to form upstanding flanges, 10 said supporting plate having slots formed transversely therein adjacent said flanges, and tongues provided at ends of the flanges and at ends of the plate adjacent the flanges, end plates and intermediate plates, the end plates having slots 15 to receive said tongues and firmly secure the end plates to the supporting plate and flanges thereof, and the intermediate plates being slotted to embrace said flanges and abut with said supporting plate between said flanges, said intermediate 20 plates having oppositely disposed recesses in the opposite edges thereof, tongues projecting from said intermediate plates within said recesses, independent metallic strip members seated in said recesses in planes offset outwardly from said 25 flanges in planes substantially parallel thereto, said strip members having apertures engaged by said tongues, sets of stator plates insulatingly supported by said strip members between said end plates and said intermediate plates, a rotor 30 shaft and sets of rotor plates carried by said shaft and adapted to be variably interleaved with said stator plates.

4. In a multiple variable condenser, a shallow channel shaped frame having upwardly extending side flanges, an assembly comprising a pair of independent flat strips extending longitudinally of said frame, insulated plates carried by said strips and depending therefrom at spaced intervals along the length thereof, said strips being disposed in planes offset from the planes of said flanges by distances substantially equal to the thickness of said insulated plates, electrostatic shields extending between said strips with their ends secured thereto intermediate the connection of said insulated plates therewith, stator plate units suspended between said insulated plates, end plates secured to the ends of said strips and to the ends of said channel shaped frame, a shaft journaled in said end plates and extending through the electrostatic shields, and rotor plates carried by said shaft and adapted to be interleaved with said stator plates.

SAMUEL COHEN. 55
